UNITED STATES PATENT OFFICE.

ALEXANDER KONOFF, OF NEW YORK, N. Y., ASSIGNOR TO OVERLAND METAL NOVELTY CO. INC., OF NEW YORK, N. Y., A CORPORATION OF NEW YORK.

DOLL'S EYE.

Application filed March 26, 1925. Serial No. 18,627.

To all whom it may concern:

Be it known that I, ALEXANDER KONOFF, a citizen of the United States, and resident of New York city, in the county and State of New York, have invented certain new and useful Improvements in Dolls' Eyes, of which the following is a specification.

This invention relates to an improvement in dolls' eyes, and particularly to the manner 10 of constructing and mounting the eye balls upon their supporting rod.

An object of the invention is to provide an eye which is of simple and inexpensive construction and which may be easily connected 15 with its supporting rod and which when so connected will be capable of universal rotary adjustment in order to properly accommodate itself to the eye socket in the doll's head.

A further and more detailed object is to 20 provide an eye including an outer hemispherical shell, preferably of metal, and bearing the eye-picture on its outer surface, and a single attaching member connected between the eye shell and its carrying rod constituting the sole element of connection 25 between said shell and rod, and further to so connect the attaching member with the shell and rod that it will provide for both a universal rotary adjustment of the shell with respect to the rod and a bodily adjustment of 30 the eye along the length of the rod.

A still further detailed object is to so construct the parts that the eye shell will be capable of a desirably limited rotary movement 35 upon the attaching member and about an axis transverse to the supporting rod, the attaching member in turn being rotatably adjustable upon the supporting rod and having a part bendable to facilitate a rotary adjustment of the eye shell upon an axis transverse both to the length of the supporting rod and to the first mentioned axis of rotation of the eye shell.

A further object is to so construct the parts 45 that they will be retained against likelihood of accidental displacement from any position into which they are manually adjusted.

Other objects and aims of the invention, more or less specific than those referred to 50 above, will be in part obvious and in part pointed out in the course of the following description of the elements, combinations, arrangements of parts and applications of principles, constituting the invention, and

the scope of protection contemplated will be 55 indicated in the appended claims.

In the accompanying drawings which are to be taken as a part of this specification, and in which I have shown merely a preferred form of embodiment of the invention:—

Fig. 1 is a front elevational view of a portion of an eye set constructed in accordance with this invention.

Fig. 2 is a rear view of the eye appearing 65 in Fig. 1.

Fig. 3 is a side elevational view of the eye seen in Fig. 2, the supporting rod being shown in transverse section upon the plane of line III—III of Fig. 2.

Fig. 4 is a transverse sectional view taken upon the plane of line IV—IV of Fig. 2.

Fig. 5 is a view similar to Fig. 2 but illustrating a modified construction of the attaching member employed.

Fig. 6 is a detailed end view of the portion of the attaching member which is adapted to engage the supporting rod, and illustrating a modified construction thereof, and

Fig. 7 is a view similar to that seen in Fig. 80 6 but illustrating a further modification.

Referring to the drawings for describing in detail the structural parts shown therein the reference character L indicates the usual bracket member by means of which the eye set is intended to be connected with the inner surface of the forehead portion of a doll.

The reference character G indicates the cross, or supporting, rod which is rotatably mounted at the lower end of the bracket 90 plate and which carries at its opposite ends the two eyes H—H.

The rod G has a pendant weight carrying arm 1 by which the eyes are gravity controlled in the usual manner.

The eyes are identical and a description of one will apply to both, as follows:

The hemispherical shell 2 has a notch 3 in one side thereof through which projects the supporting rod G.

The attaching member 4 is arranged at the rear of the shell 2 and consists of a main flat plate portion 5 and a projecting stem portion 6. The plate portion 5 is provided with a plurality of radially extending lugs 7 at its periphery adapted to overly and slidably engage with the rear annular edge surface 8 of the shell 2 at

spaced points circumferentially of said edge, and the portions of said plate intermediate the lugs 7 is arranged to underly suitable overhanging flanges as 9 which are provided 5 upon the shell continuing beyond the plane of the edge surface 8 and bent inwardly to engage the plate.

The circumferential length of the lugs 7, and their disposition with respect to the 10 flanges 9 are such as to provide unobstructed spaces as 10 between the lugs and the adjacent edges of the flanges to accommodate a certain desirable amount of rotary movement of the shell relatively to the plate, 15 the edges of the lugs and flanges serving to properly confine this adjustment within appropriate limits. The pressure of the flanges against those portions of the plate intermediate the lugs is such as to cause 20 just the proper amount of friction grip of the shell against the plate so that while rotary adjustment may be accomplished by the application of a sufficient manual force yet there will be no likelihood of any relative movement occurring in the absence of 25 such force.

In this connection it is noted that the lugs 7 are spaced considerable distances apart so that the intermediate portions of 30 the plate between said lugs is sufficiently extensive to provide for a considerable amount of flexibility, and it is further noted that if desired the flanges 9 may be suitably formed so that their central portions, 35 as at 11, are bumped forwardly thus disposing said portions so that they alone will engage the plate. By thus placing the point of contact of the flanges against the plate midway between the lugs 7 full advantage may be taken of the flexibility of 40 the plate to the end that the rotary adjustment of the shell with respect to the plate may be smoothly and easily accomplished.

The stem portion 6 of the attaching member 45 is integral with the plate portion and the material comprising it is bent so as to provide a tubular sleeve adapted to telescope over the end of the supporting rod.

The opposite edges as 12 of the material 50 forming this sleeve, as shown in Figs. 1 and 3, are not connected together. The sleeve is made normally of less internal diameter than the external diameter of the supporting rod and must be expanded when 55 forced onto the rod. In this way caused sufficient friction is provided to retain it in any position to which it is adjusted upon the rod.

As suggested in Fig. 6 the opposite edges 60 of the material forming the sleeve may if desired be constructed so that one edge thereof is turned back upon itself to provide a stop as 13 disposed to engage the other edge as 14. By this means the opposite edge portions of the material form-

ing the sleeve will be restrained against too easy spreading apart, and a greater frictional grip against the supporting rod will result. If an even greater pressure against the supporting rod is desirable the 70 stop 13 may be bent toward its carrying part, as by the use of a suitable tool, and thus provide an increased grip upon the supporting rod. Also, as seen in Fig. 7, the opposite edge portions of the material 75 forming the stem may if desired be extended and fitted with a clamp screw as 15 extending through an aperture of one edge portion and engaging within a threaded opening of the other edge portion, for 80 the same purposes referred to with respect to Fig. 6.

It may be explained here that while the use of one or the other of the expedients referred to for holding the attaching member onto the supporting rod may be utilized according to preference yet as a matter of general principle the device suggested in Fig. 6 is likely to be utilized where a larger diameter of supporting shaft is being dealt 90 with than that proposed in Fig. 3, while the device suggested in Fig. 7 would be for a successively larger shaft.

The stem portion 6, whether constructed as in Fig. 3 or in Fig. 6; or in Fig. 7, or 95 otherwise, is connected with the plate portion 5 by a small neck portion 16 which is designed and arranged so as to provide a line of bend as nearly as possible at the spherical center of the eye shell, as on the 100 line indicated X in Fig. 2, and which thus provides for a rotary adjustment of the eye shell about an axis which is transverse to the length of the supporting rod and which is also transverse to the axis of rotation of the eye shell with respect to the 105 attaching member.

The opening 3 in the eye shell is sufficiently large to accommodate all necessary 110 adjustments of the eye shell without any interference from the supporting rod, and it will be seen that by the structure described the eye shell is capable of manual rotary adjustment in all directions with respect to its supporting rod and that the center of rotation 115 is substantially at the spherical center of the eye shell, and that by reason of the telescopic engagement of the stem portion 6 upon the supporting rod the eye may be readily adjusted as an entity longitudinally of the rod.

Referring now to the modification disclosed in Fig. 5 it will be seen that the structure shown therein is the same in all respects as that herein above described except as to the manner of connecting the stem portion 6 with the plate portion 5 of the attaching member. Whereas in the structure previously described the single bendable neck portion 16 constitutes the sole element of connection between these portions the structure 120

Fig. 5 contemplates the use of two neck portions as 17 and 18. These two neck portions project from opposite sides of the stem and there is left an opening as 19 in the plate 5 beyond the end of the stem. The necks 17 and 18 are integral with the plate and stem and being of the same flexible material as said plate and stem, and being of reduced cross section, may be readily twisted so as to 10 provide for a rotary adjustment of the eye shell about an axis at or near the spherical center of the eye shell and transverse to the length of the supporting rod substantially to the same effect as previously described.

As many changes could be made in this 15 construction without departing from the scope of the invention as defined in the following claims, it is intended that all matter contained in the above description or shown 20 in the accompanying drawings, shall be interpreted as illustrative only and not in a limiting sense.

Having thus described my invention, what I claim as new and desire to secure by Letters Patent is:—

1. An eye structure comprising a semi-spherical eye shell and an attaching member by which to connect said shell with the usual supporting rod, and said attaching member comprising one portion adjustably connected 30 with the eye shell, another portion providing a sleeve to frictionally telescope over the supporting rod, and a bendable portion connecting the first two portions together.

2. An eye structure comprising a semi-spherical eye shell and an attaching member by which to connect said shell with the usual supporting rod, and said attaching member comprising one portion adjustably connected 40 with the eye shell, another portion providing a sleeve to frictionally telescope over the supporting rod, and a bendable portion connecting the first two portions together, said bendable portion being disposed to provide 45 a pivotal connection between the first two mentioned portions at a point near the spherical center of the eye shell.

3. An eye structure comprising a semi-spherical eye shell and an attaching member 50 by which to connect said shell with the usual supporting rod, and said attaching member comprising one portion adjustably connected with the eye shell, another portion providing a sleeve to frictionally telescope over the 55 supporting rod, and a bendable portion connecting the first two portions together, said portions being all formed from a single piece of sheet metal, the sleeve portion being normally of less internal diameter than the external diameter of the supporting rod and being resilient whereby it is adapted to be expanded by engagement with the supporting rod to thereby frictionally grip the supporting rod.

4. An eye structure comprising a semi-

spherical eye shell and an attaching member by which to connect said shell with the usual supporting rod, and said attaching member comprising one portion adjustably connected with the eye shell, another portion 70 providing a sleeve to frictionally telescope over the supporting rod, and a bendable portion connecting the first two portions together, said portions being all formed from a single piece of sheet metal, 75 the sleeve portion being normally of less internal diameter than the external diameter of the supporting rod and being resilient whereby it is adapted to be expanded by engagement with the supporting rod to 80 thereby frictionally grip the supporting rod together with means by which to increase the frictional grip of the sleeve upon the supporting rod.

5. An eye structure comprising a semi-spherical eye shell and an attaching member by which to connect said shell with the usual supporting rod, and said attaching member comprising one portion adjustably connected with the eye shell, another portion 90 providing a sleeve to frictionally telescope over the supporting rod, and a bendable portion connecting the first two portions together, said first mentioned portion consisting of a plate rotatably slidably engaging a rearwardly facing surface portion of the eye shell and having interengagement with other portions of the eye shell whereby its engagement with said rearwardly facing surface portion is frictioned for the purpose 95 set forth.

6. An eye structure comprising a semi-spherical eye shell and an attaching member by which to connect said shell with the usual supporting rod, and said attaching member comprising one portion adjustably connected with the eye shell, another portion 105 providing a sleeve to frictionally telescope over the supporting rod, and a bendable portion connecting the first two portions together, said first mentioned portion comprising an annular plate having circumferential spaced parts adjustably slidably engaging portions of the eye shell, and the eye shell having parts disposed to engage said plate intermediate the mentioned parts of the plate tending to flex the plate and to thereby hold the first mentioned portions of the plate 110 frictionally in any position to which the plate is adjusted with respect to the eye shell.

7. An eye structure comprising a semi-spherical eye shell, a plate at the rear of 125 said eye shell having spaced parts thereon slidably adjustably engaging a rear annular edge surface of the eye shell, flanges formed upon the eye shell arranged to engage the plate at points intermediate said mentioned parts of the plate to thereby 130

- hold said mentioned parts of the plate frictionally against the edge of the eye shell, and means whereby said plate may be connected with the usual supporting rod.
8. An eye structure comprising a semi-spherical eye shell, a plate at the rear of said eye shell having spaced lugs thereon slidably adjustably engaging a rear annular edge surface of the eye shell, flanges formed upon the eye shell arranged to engage the plate at points intermediate said lugs to thereby hold the lugs frictionally against the edge of the eye shell, and said plate having integral parts arranged to provide a pivotal connection of the plate with the usual supporting rod.
9. An eye structure comprising a semi-spherical eye shell, a plate at the rear of said eye shell having spaced lugs thereon slidably adjustably engaging a rear annular edge surface of the eye shell, flanges formed upon the eye shell arranged to engage the plate at points intermediate said lugs to thereby hold the lugs frictionally against the edge of the eye shell, and said plate having parts first to provide a sleeve for rotatably engaging over the usual supporting rod and second to provide a pivotal connection between the eye shell and the supporting rod on an axis transverse to the length of the supporting rod.
10. An eye structure comprising a semi-spherical eye shell and an attaching member by which to connect said shell with the usual supporting rod, and said attaching member comprising one portion adjustably connected with the eye shell, another portion providing a sleeve to frictionally telescope over the supporting rod, and a connecting portion connecting said first two portions together, said connecting portion extending in the direction of the length of said sleeve portion from one end of the sleeve portion and merging into the first mentioned portion and being bendable and being disposed to provide a pivotal connection between the first two mentioned portions at a point near the spherical center of the eye shell.
11. An eye structure comprising a semi-spherical eye shell and an attaching member by which to connect said eye shell with the usual supporting rod, connecting means whereby said attaching member is rotatably frictionally adjustably connected with the eye shell to permit rotary adjustment of the eye shell about a horizontal axis transverse to the length of the supporting rod, said attaching member also having a part to rotatably frictionally adjustably engage the supporting rod to permit rotary adjustment
- of the eye shell about a horizontal axis longitudinally of the supporting rod, and said mentioned connecting means for connecting the attaching member with the eye shell comprising parts to limit the rotary movement of the eye shell relative to the attaching member.
12. An eye structure comprising a semi-spherical eye shell and an attaching member by which to connect said eye shell with the usual supporting rod, connecting means whereby said attaching member is rotatably frictionally adjustably connected with the eye shell to permit rotary adjustment of the eye shell about a horizontal axis transverse to the length of the supporting rod, said attaching member also having a part to rotatably frictionally adjustably engage the supporting rod to permit rotary adjustment of the eye shell about a horizontal axis longitudinally of the supporting rod, and said attaching member further having a bendable part bendable to cause rotary adjustment of the eye shell about a vertical axis transverse to the length of the supporting rod.
13. An eye structure comprising a semi-spherical eye shell and an attaching member by which to connect said eye shell with the usual supporting rod, connecting means whereby said attaching member is rotatably frictionally adjustably connected with the eye shell to permit rotary adjustment of the eye shell about a horizontal axis transverse to the length of the supporting rod, and said attaching member further having a bendable part bendable to cause rotary adjustment of the eye shell about a vertical axis transverse to the length of the supporting rod.
14. An eye structure comprising a semi-spherical eye shell and an attaching member by which to connect said eye shell with the usual supporting rod, connecting means whereby said attaching member is rotatably frictionally adjustably connected with the eye shell to permit rotary adjustment of the eye shell about a horizontal axis transverse to the length of the supporting rod, and said attaching member comprising a flexible plate having parts resting against rear surface parts of the eye shell, and the connection between said attaching member and the eye shell comprising inwardly projecting parts of the eye shell engaging the plate and holding the plate flexed against the mentioned rear surface portions of the eye shell.

In testimony whereof I affix my signature.

ALEXANDER KONOVOFF.
